UNITED STATES PATENT OFFICE.

GEORGE HERREN, OF GREAT BEND, KANSAS.

RADIATOR-VALVE.

1,196,688.

Specification of Letters Patent. Patented Aug. 29, 1916.

Application filed August 7, 1915. Serial No. 44,302.

To all whom it may concern:

Be it known that I, GEORGE HERREN, a citizen of the United States, residing at Great Bend, in the county of Barton and 5 State of Kansas, have invented new and useful Improvements in Radiator-Valves, of which the following is a specification.

This invention relates to radiator valves or valves especially designed for use in connection with steam radiators, whereby the 10 steam and water of condensation are trapped in an effective and noiseless manner and the water of condensation drained from the valve back into the radiator and to the return 15 pipe of the heating system.

Another object of the invention is to provide novel means for adjusting the seating of the controlling valve while at the same time admitting of the use of the silencer 20 hereinafter particularly described.

With the above and other objects in view, the invention consists in the novel construction, combination and arrangement of parts, as herein described, illustrated and claimed.

In the accompanying drawings:—Figure 25 1 is a vertical diametrical section through a radiator valve embodying the present invention. Fig. 2 is a cross section through the same on the line 2—2 of Fig. 1, looking 30 upwardly. Fig. 3 is a fragmentary vertical section on the line 3—3 of Fig. 1. Fig. 4 is a detail perspective view of the cap removing and seat adjusting tool to be used in connection with the valve.

Referring to the drawings 1 designates a 35 radiator and 2 the vent pipe thereof.

In carrying out the present invention I provide a noiseless valve which in the preferred embodiment thereof comprises a substantially cylindrical main steam and condensation chamber 3 which is supported by the pipe 2, the latter communicating with the bottom of the chamber 3 as clearly shown in Fig. 1.

40 4 designates a gravity drain pipe which extends from the chamber 3 back to the radiator, the pitch or inclination of said pipe being such as to cause the water to readily find its way into the radiator and 45 from thence through the return pipe of the system to the boiler.

The chamber 3 is provided with a removable cap 5 preferably threaded therein as shown and provided at diametrically opposite points with knobs or studs 6 adapted 50 to be engaged by a combined screw driver

and spanner shown in Fig. 4, the main body of the spanner being in the form of an annulus 7 formed with notches 8 to engage the studs or knobs 6 of the cap 5 thereby 60 enabling said cap to be removed. Extending radially outward from the annulus 7 is an arm 9 the end portion of which is formed into a screw driver point 10 for adjusting the valve seat as will hereinafter appear. 65

The cap 5 is formed with a central internally threaded opening 11 to receive the threaded lower end of a valve chamber or cage 12 in which works a valve 13. The valve cage or chamber 12 is internally 70 threaded in the upper end thereof to receive a valve seat 14, the same being threaded into the cage and formed with an internal cone shaped seating face 15 at its lower end against which the correspondingly cone 75 shaped face 16 of the valve is adapted to rest under certain conditions.

The valve 13 is provided with a stem 17 extending downwardly within the chamber 3 and having fixedly attached thereto a 80 valve controlling and extensible chamber or thermostatic element 18 which expands under the head of the steam impinging thereon and serves thereby to force the valve stem 17 upwardly and close the valve 13 against 85 its seat. A short stem or stud 17' on the bottom of the controlling member 18 is seated in an opening 19 in an elevated step or guide 20 fastened in the bottom of the chamber 3 as shown. The member 18 may comprise 90 one or more chambers adapted to contain, for example, ether, alcohol and distilled water which at a certain temperature will cause the member 18 to expand and thereby force the valve 13 against its seat. The 95 valve seat 14 is adjustable by providing the same in the upper extremity thereof with a diametrical notch 21 in conjunction with which the point 10 of the tool may be used for effecting the desired adjustment of the 100 seat so that the valve 13 will close at any desired temperature.

Surrounding and inclosing the major portion of the valve cage or chamber 12 is a silencer embodying a hollow cylindrical body or shell 22 the upper end of which is normally closed by means of a cap 23 having a threaded connection with the body or shell 22. The bottom wall of said shell is formed with a central opening 24 of sufficient size to enable the silencer to be slid on and off the valve cage 12 and is also 110

formed with a number of ports or vents 25. The shell or body 22 contains a number of superimposed rings 26 of fibrous material such as felt and wool which encircle the 5 valve cage 12, rings 27 of wire gauze being arranged above and below the pile or column of packing rings, the lower gauze ring resting against the bottom wall of the silencer and the top gauze ring being held 10 down by the flange of the cap 23 thus confining and holding all of said rings in proper position at all times. These rings may be removed and replaced or renewed as frequently as found necessary.

15 The live steam enters the chamber 3 through the pipe 2 and comes in direct contact with the controller or thermostatic member 18. This becomes heated and effects a closing of the valve 13 against its seat thereby shutting off the steam and preventing the same from escaping into the room. The steam escaping into the silencer is muffled by the rings of fibrous material thereby making the device noiseless at all 20 times. As the heat subsides, the coolor water of condensation within the chamber 3 causes the member 18 to contract, assisted by a coiled expansion spring 28 which encircles the valve stem and is interposed between the member 18 and the cap 5 as 25 shown in Fig. 1. This will cause the valve 13 to open and again admit steam to the 30

silencer. The water of condensation will escape through the drain pipe 4 and return through the radiator and return pipe to the 35 boiler of the heating system.

Having described my invention, I claim:—

In a steam radiator valve, the combination with the outlet of a radiator, of a steam condensation chamber in direct communication therewith, a valve chamber extending from and located exteriorly of but communicating with said condensation chamber, a valve seat in said valve chamber, a valve movable toward and away from said seat and having a stem, a thermostatic valve controlling member located in the condensation chamber and having the valve stem attached thereto, and a detachable silencer 40 inclosing said valve chamber only and comprising a tubular shell, a tubular body of fibrous packing within said shell, and reticulated packing retaining means adjacent to the opposite ends of said shell, the outer 45 end of said cap being closed and the inner end thereof being formed with vents.

In testimony whereof I affix my signature in presence of two witnesses.

GEORGE HERREN.
